US0D1009609S

(12) **United States Design Patent** (10) **Patent No.:** **US D1,009,609 S**
(45) **Date of Patent:** **** Jan. 2, 2024**

(54) **WIRE POSITIONING DEVICE**

(71) Applicant: **Affordable Wire Management, LLC**, Somerville, NJ (US)

(72) Inventors: **Scott Robert Rand**, Somerville, NJ (US); **Daniel Robert Smith**, Gilbert, AZ (US); **Peter Mark Hruby**, Scottsdale, AZ (US)

(73) Assignee: **Affordable Wire Management, LLC**, Somerville, MA (US)

(**) Term: **15 Years**

(21) Appl. No.: **29/792,207**

(22) Filed: **Mar. 11, 2022**

(51) LOC (14) Cl. **08-11**

(52) U.S. Cl.

USPC **D8/367**

(57) **CLAIM**

The ornamental design for a wire positioning device, as shown and described.

DESCRIPTION

FIG. 1 is a top perspective view of a wire positioning device; FIG. 2 is a bottom perspective view of the wire positioning device of FIG. 1;

FIG. 3 is a front view of the wire positioning device of FIG. 1;

FIG. 4 is a back view of the wire positioning device of FIG. 1;

FIG. 5 is a left side view of the wire positioning device of FIG. 1;

FIG. 6 is a right side view of the wire positioning device of FIG. 1;

FIG. 7 is a top view of the wire positioning device of FIG. 1; and,

FIG. 8 is a bottom view of the wire positioning device of FIG. 1.

1 Claim, 8 Drawing Sheets
